US0D1099853S

(12) **United States Design Patent** (10) Patent No.: **US D1,099,853 S**
(45) Date of Patent: ** Oct. 28, 2025

(54) **CONTROLLER PORTION**

(71) Applicant: **Microsoft Corporation**, Redmond, WA (US)

(72) Inventors: **Christopher Hays Kujawski**, Bellevue, WA (US); **Kaitlyn Sabina Jones**, Redmond, WA (US); **Benjamin Edward Newton**, Van Buren Township, MI (US); **Giulia Valeria Elli**, Seattle, WA (US)

(73) Assignee: **Microsoft Technology Licensing, LLC**, Redmond, WA (US)

(**) Term: **15 Years**

(21) Appl. No.: **29/928,261**

(22) Filed: **Feb. 9, 2024**

(51) LOC (15) Cl. **14-02**

(52) U.S. Cl.

USPC **D14/388**; D14/412; D21/333

(57) **CLAIM**

The ornamental design for a controller portion as shown and described.

DESCRIPTION

FIG. 1 is a rear perspective view of a controller portion showing our new design;

FIG. 2 is a front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the controller portion that form no part of the claimed design.

1 Claim, 7 Drawing Sheets
